UNITED STATES PATENT OFFICE.

EDWARD F. DEACON, OF ST. LOUIS, MISSOURI, ASSIGNOR TO GUS V. BRECHT BUTCHERS' SUPPLY COMPANY, OF ST. LOUIS, MISSOURI, A CORPORATION OF MISSOURI.

SAUSAGE STUFFER.

Application filed May 27, 1922. Serial No. 564,039.

To all whom it may concern:

Be it known that I, EDWARD F. DEACON, a citizen of the United States of America, residing at the city of St. Louis, State of Missouri, United States of America, have invented a certain new and useful Sausage Stuffer, of which the following is such a full, clear, and exact description as will enable any one skilled in the art to which it appertains to make and use the same, reference being had to the accompanying drawings, forming part of this specification.

My invention relates to compressing machines and particularly to sausage stuffing machines of the type wherein an air actuated piston forces sausage or other comminuted products into edible casings in which they are sold and the object of the invention is to provide safety means whereby the piston 10 may not be accidentally blown out of the cylinder of the machine when the head is removed for cleaning purposes. These machines are usually large with very heavy pistons and accidental forcing of the piston 20 out of the cylinder may result in injury to workmen and considerable property damage.

In the accompanying drawings which illustrate my invention, Figure 1 is a side view of a sausage stuffing machine to which 30 the invention is applied; Figure 2 is a vertical cross sectional view; Figure 3 is a top plan view; and Figures 4, 5, and 6 are detail views showing the operating valve and valve locking mechanism to which my invention relates.

1 represents the cylinder of the machine and 2 the piston, loosely mounted therein, which is actuated by compressed air received through pipe 3 to force the piston up in the 40 cylinder and expel the contents of the cylinder through the openings 4 into the containing casings, not shown. The head 5 of the cylinder is adapted to be removed for the purport of filling the cylinder and of cleaning it, this head being connected by means of the threaded member 6 to the clamping yoke 7. One end of this clamping yoke is held in pivoted relation with the cylinder by means of the bolt 8 and the other end is held in engagement with the cylinder by the bolt 9 which in the closed position of the head lies in the laterally opening groove 10 in an integral lateral extension of the cylinder wall. The head is removed from the 50 cylinder by lifting it out of engagement 55

therewith by means of the screw 6 and then turning the clamp 7 on the pivot 8 and it is to means preventing this pivotal movement of the clamp 7 to remove the head from the alignment with the end of the cylinder that 60 my invention relates, the object of the invention being, as above indicated, to prevent this shifting of the head when the valve controlling the admission of air to the rear of the piston is open and to prevent the opening of the valve while the cylinder head is 65 out of alignment with the end of the cylinder.

A supply pipe 11 from a suitable air compressor, not shown, is connected to the 70 supply pipe 3 through the valve 12 and connected to the moving part of this valve is a latch member 13 pivoted to an extension of the cylinder wall at 14, the connection between the valve and latch member comprising 75 a slot in the latch, and a pin 15 attached to the valve as shown. In the open position of the valve, the end of the latch 13 extends in the path of motion of the head of the bolt 9 in the clamping yoke 7 and therefore prevents the pivotal movement of this clamp which is necessary to remove the cylinder 80 head from alignment with the cylinder. The relative position of the parts when the valve is open is shown in Figures 4 and 6. 85

When the cylinder head is in position on the cylinder, and as shown in Figure 4, the head of the bolt 9 engages with a sliding latch locking member 16 which member carries the latch locking pin 17. When the yoke 90 is swung to open position and 9 is brought out of engagement with 16 the spring 18 raises 16 and brings the pin 17 into position where it may enter the slot 19 in the latch member 13, this slot having been brought 95 to a vertical position by the closing of the air valve which necessarily preceded the swinging of the yoke 7 out of its closed position. The conformation of this slot 19 with relation to the pin 17 is such that the valve cannot be opened until the pin is removed from the slot which action does not take place, of course, until the tapered end of the bolt 9 engages with the tapered end of the member 16 when the yoke is brought to closed position. 100

In the drawings, the numeral 20 indicates the air vent pipe for releasing the air pressure in the cylinder when the valve is closed and 21 indicates a bypass valve of relatively 110

small opening through which air may be admitted for the purpose of raising the piston to the top of the cylinder when it is desired to remove the piston therefrom. When 5 said piston is brought to the top of the cylinder it is connected to the pivoted arm 23 by means of the bolt 22. This arm, by means of rack and pin connection with the handle 24, may be elevated and the piston brought 10 to position to be swung to one side and access can thus be had to all parts of the piston and interior of the cylinder for cleaning purposes.

The operation of my improved safety 15 means will be apparent from the foregoing description, and it will be noted accidental forcing of the piston out of the cylinder while the head is off or the release of the head clamping yoke while the valve is open 20 are automatically prevented.

Having fully described my invention, what I claim as new and desire to secure by Letters Patent of the United States is:

1. In a device of the class described, the 25 combination with a compression cylinder having a removable head, a liquid actuated piston in the cylinder, a valve controlling admission of liquid to the cylinder, and means connected to the valve for locking it 30 in closed position, said means being positioned to prevent removal of the cylinder head when the valve is in open position.

2. In a device of the class described, the 35 combination with a compression cylinder having a removable head, a liquid actuated piston in the cylinder, a valve controlling admission of liquid to the cylinder, a pivoted support for the removable head, and means connected to the valve for locking it 40 in closed position, said means being positioned to prevent the swinging of the head support on its pivot when the valve is in open position.

3. In a device of the class described, the 45 combination with a compression cylinder having a removable head, a liquid actuated piston in the cylinder, a valve controlling admission of liquid to the cylinder, means

connected to the valve for locking it in closed position, said means comprising a locking member tending to move to locking position, and means operative only when the removable cylinder head is in alignment with the cylinder for holding said first mentioned means in unlocking position. 55

4. In a device of the class described, the combination with a compression cylinder having a removable head, a liquid actuated piston in the cylinder, a valve controlling admission of liquid to the cylinder, locking 60 means connected to the valve and a locking pin for engaging said locking means when the valve is in closed position, the position of said locking pin being controlled by the position of the removable head. 65

5. In a device of the class described, the combination with a compression cylinder having a removable head, a liquid actuated piston in the cylinder, a valve controlling admission of liquid to the cylinder, a clamping yoke attached to the removable head and pivoted at one end, a clamping member carried by the other end of the yoke and engaging the cylinder when the head is in position thereon, a locking latch connected to 70 the valve and extending in the path of said clamping member when the valve is open. 75

6. In a device of the class described, the combination with a compression cylinder having a removable head, a liquid actuated piston in the cylinder, a valve controlling admission of liquid to the cylinder, a clamping yoke attached to the removable head and pivoted at one end, a clamping member carried by the other end of the yoke and engaging the cylinder when the head is in position thereon, a locking latch connected to 80 the valve and extending in the path of said clamping member when the valve is open, a locking pin to engage said latch when the valve is closed, said locking pin being actuated by the clamping member carried by 85 the yoke. 90

In testimony whereof, I have hereunto set my hand and affixed my seal.

EDWARD F. DEACON. [L.S.]
